UNITED STATES PATENT OFFICE.

THOMAS W. STEWART, OF SOUTH SIOUX CITY, NEBRASKA.

SAFETY RAZOR.

Application filed November 2, 1920. Serial No. 421,262.

To all whom it may concern:

Be it known that I, THOMAS W. STEWART, a citizen of the United States, and a resident of South Sioux City, in the county of Dakota and State of Nebraska, have invented 5 certain new and useful Improvements in Safety Razors, of which the following is a specification.

My present invention relates, no doubt, to 10 safety razors, yet it is more particularly intended for scraping or shaving carcasses, the invention having, for its principal object, the production of an improved and simplified device for removing hair from 15 those portions of the carcasses which the means usually employed for the purpose fail to reach.

A further object of the invention is the 20 production of a carcass-scraping device particularly adapted for scraping hair from convex and concave surfaces of carcasses.

Furthermore, the invention contemplates 25 a carcass-scraping device comparatively inexpensive and simple in construction and thoroughly efficient in operation.

These and other objects and advantages I 30 successfully attain in the embodiment hereinafter defined in the appended claims and illustrated in the accompanying drawings, of which:

Fig. 1 is a plan of the device of my invention, as constructed for shaving concave surfaces.

Fig. 2 is a rear elevation thereof, a part 35 being cut away.

Fig. 3 is an enlarged transverse section of the same, parts being cut away.

Fig. 4 is a plan of the device as constructed for shaving convex surfaces, and

Fig. 5 is a rear elevation thereof.

While I have illustrated and hereinafter described a preferred embodiment of the invention, I would not be understood as being limited to such specific construction, for 45 various alterations and modifications may be made in the details of construction and arrangements of parts herein disclosed without departing from the spirit and scope of the invention as defined in the appended 50 claims.

Referring now more particularly to Figures 1 to 3, 5 represents the guard or blade-supporting means, which consists of an elong-

gated plate, bent longitudinally, forming in 55 plan view a crescent shape, as presented in Fig. 1, the lower edge of the said plate being notched, as at 6, exposing the sharp edge of a blade, 7, held firmly in conformity with and against the outer or front face of the plate, 5, as by providing overturned ends, 8, 60 on the guard-plate, 5, which engage the ends of the blade, 7, the intermediate portion of the guard-plate is provided with means serving both as a handle for the device and means for firmly clamping the blade and 65 guard-plate together, the said means preferably consisting of a short cylinder, 9, positioned above the device and having a depending part, 10, suitably secured, as at 11, to the intermediate portion of the guard. 70

Within the cylinder, 9, freely rotates a cylindrical nut, 12, provided at its forward end with a boss, 13, which prevents rearward movement of the nut, its rear end being reduced, as at 14, to enter and be secured 75 to a suitable handle, 15, which prevents forward movement of the nut, yet permits free rotation of the latter within the cylinder, 9. Into the nut, 12, is threaded a bolt, 16, projecting rearwardly from a plate, 17, which 80 embraces the front of the intermediate portion of the blade, 7. By virtue of this construction, it is clear that rotation of the handle in one direction clamps the blade firmly to the guard, while rotation in the opposite 85 direction will loosen, and permit separation of the parts.

The frame above set forth is obviously intended for application to concave surfaces or recesses which would not be reached readily 90 by a straight blade while the form shown in Figs. 4 and 5 is for use on convex surfaces, the guard plate, 5, being concavo-convex, but bent oppositely to the previously 95 described construction, and the blade, 7, being positioned on the concave side thereof, and its intermediate portion held firmly against the plate by means of the handle, 15, and associated parts.

Having thus described my invention, what 100 I claim as new and desire to secure by Letters Patent of the United States is:

A device of the class described comprising an elongated rigid guard plate curved longitudinally in a crescent shape, the end portions of the plate being overturned, a sharp-

edged blade resting against the face of the plate and engaged by said overturned end portions, and a handle and securing means, including a clamp member engaging the intermediate portion of the exposed face of the blade, a bearing member carried by the plate, a handle, a nut fixed on the handle

and rotatable within the bearing member, and a bolt projecting from the clamping member, and threaded into the nut. 10

In testimony whereof, I have hereunto set my hand this 19th day of October, 1920.

THOMAS W. STEWART.
